UNITED STATES PATENT OFFICE

VESS JONES, OF NEW YORK, N. Y.

CONTAINER

Application filed January 19, 1929. Serial No. 333,719.

This invention relates in general to portable one piece card board containers for packing bottles for easy distribution and display.

One of the objects of this invention is the provision of a one piece card board container suitably shaped so that when folded along predetermined lines, it will provide a simple and handy container for bottles by means of which they may be easily carried about.

10 A further object of this invention is the provision of containers of this nature which are easy to store when not in use.

15 A further object of this invention is the provision of a container of this nature which may be easily folded up along predetermined lines to form a carrier for bottles and the like by means of which they may be shipped, carried and displayed.

20 A further object of this invention is the provision of containers of this nature which are relatively simple in structure, adapted for cheap and rapid manufacture and efficient and rugged in use.

25 These and many other objects as will appear from the following disclosure are secured by means of this invention.

30 This invention resides substantially in the combination, construction and relative location of parts all as will be set forth more fully hereinafter.

Referring to the drawings,

Figure 1 is a plan view of the single piece comprising one form of container;

35 Fig. 2 is a side elevational view of the piece folded up to form the container;

Fig. 3 is an end elevational view of the arrangement of Fig. 2;

Fig. 4 is a perspective view of a modified form of container;

40 Fig. 5 is a cross sectional view taken on the line 5--5 of Fig. 4;

Fig. 6 is a sectional view of the material used in the containers; and

45 Figs. 7 and 8 are perspective views of modified forms of containers having display openings;

Fig. 9 is a perspective view of a modified form of container showing a different arrangement for closing it.

50 A detail reference to the drawings will now

be made in order that the principles of construction and operation of this device may be understood. The container consists of one piece blank formed of suitable card board material such as is now normally used in packing cartons. The container blank consists of the parts 1, 2, 3, 4 and 5. The parts 2 and 3 are united with part 1 along its edges and the parts 4 and 5 are united with the parts 2 and 3 respectively along their edges. 60 The outer edge of the parts 4 and 5 are provided with the short narrow strips 6 and 7 respectively. The parts 1, 2, 3, 4 and 5 are provided at each end with the parts 10, 11, 9, 12 and 8 respectively. Actually all these 65 parts are formed of one single integral piece and delineated from each other by lines of fold indicated by dot and dash lines in the drawings. The parts 8, 9, 10, 11 and 12 are separated by slots as clearly shown in the 70 drawings. The parts 4 and 5 are provided with elongated openings 13. When the blank is folded up along the lines of fold the result is the container of the form shown in Figs. 2 and 3. The bottles or other objects are 75 supported on the part 1 which forms the base of the container. In folding up the blank the small ends 10 are first placed at right angles to the part 1. The parts 2 and 3 are then folded upwardly at right angles to the 80 part 1 and the end parts 9 and 11 are folded at right angles to the parts 2 and 3 so as to meet as shown in Fig. 2 and enclose the end parts 10.

The parts 6 and 7 are folded so as to be a 85 right angles to the parts 4 and 5 and then the parts 4 and 5 are inclined to the side parts 2 and 3 as is clearly shown in Fig. 3. The end parts 8 and 12 are then folded to meet the line as clearly shown in Fig. 3. The result is that the two ends and the top of the container are formed by the parts which abut each other which abutting joints can then be sealed over and secured by means of gummed strips of paper. The openings 13 are now 95 in alignment and form a handle by means of which the container may be carried.

The arrangement shown in Figs. 4 and 5 differs in that the line of closure which occurred at the top of the container in the first 100

form is now at the side. The container is shown comprising the narrow strip 14, the side portions 16 and 15, the inclined portions 21 and 23 and the top portion 22. The side portion 15 is provided with the end pieces 17; the side portion 16 is provided with the end pieces 18; the base portion 14 is provided with the small tabs 27; the side portion 21 is provided with the end pieces 19; the side portion 23 is provided with the end portions 20 and the top portion 22 is provided with the short tabs 24; the side portions 21 and 23 are provided with elongated openings 25. In this case the one piece blank 15 is again folded along the lines of fold but instead of having the sides abut along the line at the top the portions 21 and 15 abut along the line 26. As before all the butt joints may be sealed and secured by means of gummed 20 tape.

The difference of the arrangement in Figs. 7 and 8 is that display windows of any suitable form as shown at 30 and 31 may be provided through which the contents of the 25 container may be displayed. These windows may be applied to any form of device. By means of this simple structure a very convenient container is secured by means of which bottles and the like in a number 30 pending upon the size of the container may be packed for shipment, distribution and display.

The form of the device shown in Figure 9 differs in one or two respects from the other 35 forms disclosed. In general the structure is like that of Figure 4 in that the line of closure is at 40 corresponding to the line of closure 26 in Figure 4. In this form of device however the end pieces 19 and 20 are eliminated so 40 that the ends of the cover or closure portion of the container are open. The joints at the ends formed by the flaps corresponding to the flaps 17 and 18 in Figure 4 may be sealed and secured together by gummed tape. The 45 cover for the container may be held closed by means of the arrangement shown comprising buttons 41, secured to the main body portion and to the cover, and strings 42 secured at one end to the buttons on the cover and 50 wrapped at their other ends around the buttons on the main body portion. By means of this arrangement the container can be easily opened and held closed without the use of gummed tape.

55 Features of this invention reside in certain principles of construction and operation which have been illustrated in several forms in the drawings for purposes of disclosure. It is of course apparent that these 60 principles may be embodied in many other physical forms without departing from the principle and scope of the invention as defined in the appended claims to which I desire to be limited rather than by the disclosure.

What I seek to secure by United States Letters Patent is:

1. In a container made of a one piece blank the construction comprising a single body of flexible material having at least seven united 70 portions delineated by lines of fold between said portions, at least five of said seven portions having end pieces secured thereto but separated from each other by slots, said blank being adapted to be folded along the lines of 75 delineation and the end pieces being adapted to be folded at the point where they unite with the said parts to form a closed container having a flat bottom and sides comprising straight and inclined portions, the inclined 80 portions of the sides having openings to provide a handle for the container.

2. In a container made of a one piece blank the construction comprising a single body of flexible material having at least seven united 85 portions delineated of lines of fold between said portions, at least five of said seven portions having end pieces secured thereto but separated from each other by slots, said blank being adapted to be folded along the lines 90 of delineation and the end pieces being adapted to be folded at the point where they unite with the said parts to form a closed container having a flat bottom and sides comprising straight and inclined portions, the inclined 95 portions of the sides having openings to provide a handle for the container, at least one of said sides having openings therein by means of which the contents of the container 100 may be displayed.

In testimony whereof I have hereunto set my hand on this 15 day of January, A. D., 1929.

VESS JONES.
